FIG.1

FIG. 2

FIG.3

FIG. 4

FIG.5

FIG.6

FIG. 1 is a side elevational view of a luggage case showing my new design;

FIG. 2 is a top plan view thereof;

FIG. 3 is an end elevational view thereof;

FIG. 4 is a perspective view thereof in partially opened condition;

FIG. 5 is an enlarged fragmentary end view thereof showing details of the luggage case;

FIG. 6 is a further enlarged fragmentary side view of one corner of the luggage case.

The side not shown is substantially similar to the side shown in FIG. 1, and the bottom, not shown, is ornamented substantially similar to the ornamentation of the top with the omission of the handle and lock fasteners.

I claim:

The ornamental design for a luggage case, substantially as shown and described.
